UNITED STATES PATENT OFFICE.

CARL H. LIEBER, OF INDIANAPOLIS, INDIANA, ASSIGNOR TO THE H. LIEBER COMPANY, OF INDIANAPOLIS, INDIANA, A CORPORATION OF INDIANA.

PICTURE-FRAME AND BASE.

1,256,337.

Specification of Letters Patent. Patented Feb. 12, 1918.

Application filed May 1, 1916. Serial No. 94,573.

To all whom it may concern:

Be it known that I, CARL H. LIEBER, a citizen of the United States, residing at Indianapolis, in the county of Marion and 5 State of Indiana, have invented a new and useful Picture-Frame and Base, of which the following is a specification.

It has heretofore been proposed to provide picture frames with pedestals or bases 10 attached to the frames in such manner as to support the said frames in an upright or slightly backwardly inclined position upon a table, but, as heretofore produced, such bases have had to be attached to the frames 15 in the factory because unskilled operatives were apt to ruin the frames by an improper insertion of the fastening screws. Combined frames and bases so manufactured are objectionable for several reasons, among 20 which are, first, that when the base and frame are combined in the factory, a dealer must carry a very large stock of goods in order to offer a satisfactory variety, and, second, the combined structure is exceedingly 25 difficult to pack and ship.

The object of my present invention is to produce a separate pedestal and attaching piece of such character that the pedestals and fastening pieces can be manufactured 30 independently and carried in stock by the dealer and readily associated without great skill with any desired frame, whereby many different combinations from a comparatively small stock may be produced.

35 The accompanying drawings illustrate my invention. Figure 1 is a perspective view of my improved base and an associated frame; Fig. 2 a perspective view of the base and separate fastening member; Fig. 3 a transverse section of the base; and Fig. 4 a section of a slight modification.

In the drawings, 10 indicates a base of any desired configuration, ornamentation and size, provided in its upper face with a 45 narrow slot 11 which is preferably slightly rearwardly inclined, as indicated in Fig. 3, the upper surface 12 of the base being preferably slightly inclined so as to lie at right angles to the direction of the slot.

50 The frame 13 may be of any desired character and will be associated with the base 10 by means of a connecting piece 14 having a thickness substantially equal to the width of slot 11; a width no greater than the depth 55 of slot 11, and a length considerably less

than the length of slot 11. This fastening piece 14 will be conveniently provided with a pair of screw holes 15 adapted to receive ordinary wood screws in such manner that said screws may be passed through 60 the width of the fastening piece and into the lower bar of frame 13. These screws may be comparatively small in diameter so that they may readily enter the frame 13 and no great care in placing the same is 65 necessary, because, the fastening piece 14 being considerably shorter than the length of slot 11, any inaccuracies of placement of the fastening member relative to the frame may be compensated by a slight shifting of 70 the fastening piece within the slot 11.

Bases constructed in accordance with the above description may be manufactured in standard sizes and largely varied patterns and carried in stock by a picture frame 75 dealer. Most conveniently each base should be accompanied by a properly proportioned fastening member 14, made conveniently to carry two necessary fastening screws, but the fastening piece 14 might be supplied by 80 the dealer, if desired.

When the parts have been assembled as described, the frame with the attached piece 14 may be at any time readily withdrawn from the base and the base and frame thus 85 become more easily packed for shipment without danger of breaking the glass in the frame or the connection between frame and base.

In Fig. 4 the piece 14 has a width, or 90 substantially vertical dimension, which is very materially greater than the depth of slot 11 so that, instead of being fastened to the under edge of the frame 13, it may be fastened to the back of the frame near its 95 lower edge. This does not produce quite as satisfactory a construction as that shown in Figs. 1-3, inclusive, because the piece 14 is not entirely hidden when the frame is placed upon the base. 100

I claim as my invention:

1. As an article of manufacture, a picture frame base having a closed-end slot in its upper face slightly rearwardly inclined, and an associated strip having a thickness substantially equal to the width of the slot and a length materially less than the length of the slot, said associated member being separate from and adapted for easy attachment 105 to the lower bar of a picture frame. 110

2. As an article of manufacture, a picture frame base having a closed-end slot in its upper face, and an associated strip having a thickness substantially equal to the width ⁵ of the slot and a length materially less than the length of the slot, said associated member being separate from and adapted for

easy attachment to the lower bar of a picture frame.

In witness whereof, I have hereunto set my hand at Indianapolis, Indiana, this 24th day of April, A. D. one thousand nine hundred and sixteen.

CARL H. LIEBER.
